DESIGN FOR A SERVING TRAY OR THE LIKE

Yves C. Le Guillou, New York, N. Y.

Application May 6, 1939, Serial No. 84,831

Term of patent 14 years

To all whom it may concern:

Be it known that I, Yves C. Le Guillou, a citizen of the Republic of France, residing at New York, in the county of New York and State of New York, have invented a new, original, and ornamental Design for a Serving Tray or the like, of which the following is a specification, reference being had to the accompanying drawing, forming part thereof.

In the drawing:

Fig. 1 is a top plan view of the serving tray or the like, showing my new design; and

Fig. 2 is a fragmentary cross-sectional view thereof taken along the line 2—2 of Fig. 1.

The characteristic feature of the design resides in the portion shown in full lines and it will be understood that this portion is repeated throughout the entire serving tray indicated in dot and dash lines.

I claim:

The ornamental design for a serving tray or the like, substantially as shown and described.

YVES C. LE GUILLOU.
